RAIL TIE

Ignacz Windisch, Arad, Rumania

Application October 4, 1932, Serial No. 636,145

3 Claims. (Cl. 238—59)

This invention relates to new and useful improvements in a railroad tie.

The invention has for an object the construction of a railroad tie which is characterized by a body element for extending transversely beneath a pair of rails and which is provided with a pair of substantially U-shaped top projections for engaging against the outer sides of the rails with the bends towards the rails and the arms at right angles to the rails.

Furthermore, as another object of this invention it is proposed to provide the body element with an inner pair of projections and clamp plates for engaging thereon and abutting against the inner sides of the pair of rails.

Furthermore, it is proposed to arrange the central portion of the tie with a treadle section for convenience in walking.

As another object of this invention it is proposed to construct the body element with the U-shaped top projections of separate material and detachably connected.

The invention still further proposes the construction of a device of the class described which is of simple durable construction, dependable in use and efficient in operation and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a transverse sectional view of a railroad tie constructed according to this invention.

Fig. 2 is a plan view of the tie.

Fig. 3 is a view similar to Fig. 1 but showing the tie applied to a pair of rails.

Fig. 4 is an enlarged detailed view of one of the clamping elements shown in Fig. 3.

Fig. 5 is a plan view of the clamping element.

Fig. 6 is a plan view of a cotter pin used in holding the clamping blades down.

Fig. 7 is an edge view of Fig. 6.

Fig. 8 is a plan view of the railroad tie and a portion of rail.

Fig. 9 is a view similar to Fig. 1 but illustrating a modified form of the device.

Fig. 10 is an enlarged detailed view of a portion of Fig. 9.

The railroad tie, according to this invention, comprises a body element 10 for extending transversely across and beneath a pair of rails 11. The

body 10 is formed with a pair of substantially U-shaped projections 12 for engaging against the outer sides of the rails 11 and formed with the bends towards the rails and the arms at right angles. These projections have straight inner edges 13 and sides 14 at right angles thereto. These projections are hollowed out at the rear 15 which hollowing-out forms the U-shape previously mentioned. The inner sides 13 are recessed at the bottom 16 for receiving the bottom flange 65 of the rail.

An inner pair of projections 17 from the body element serve as anchor posts for clamp plates 18 which engage against the inner sides of the rails 11 and more particularly, against the bottom flanges thereof. The clamp plates 18 are formed with openings 19 adapted to engage over the projections 17. A treadle portion 20 is formed on the top of the body and is knurled, as indicated by reference numeral 21 for use when one walks on the ties. The clamp plates 18 are of such size that their rear ends 22 engage against the sides of the treadle portion 20.

A means is provided for holding down the clamp plates and comprises a cotter pin 23 for each of the projections 17. These projections are formed with transverse apertures for receiving the cotter pins. The cotter pin 23 tapers from the front end 25 to the rear so that it may be driven through the opening 24 and tightly clamp the clamping plate down. After it is engaged in place the ends should be turned out as clearly indicated in Fig. 8. Directly beneath the rails 11 the body 10 is formed with protuberances 26 which serve to reinforce the body at these points. At the edges the body 10 is formed with flanges 27 adapted to engage upon a railroad bed. One of the rails 11 is shown composed of sections with the ends 28 meeting at the center of the projection 12. This particular projection is formed with peg portions 29 engaging through apertures in the sides of the rail sections so as to constitute the joint between the rail sections.

In Figs. 9 and 10 a modification of the invention has been disclosed in which outer clamp elements 30 are shown for engaging against the outer sides of the rails. The clamp element 30 is substantially identical with the projection 12 except that it is formed from a separate piece arranged upon the body 10. A means is provided for securely holding the element 30 in place when a rail is in place upon the tie. This means comprises a recess formed in the body 10 and of a shape so that the clamping piece 30 may engage therein at an inclination to the vertical directed outwards. A

clamping plate 32 is slidable within the body 10 and adapted to engage in a slot 33 formed in the clamp element 30. The plate 32 is connected with a bell crank 34 pivotally mounted at 35. A 5 vertical peg 36 connects with the other end of the bell crank 34 and projects upwards above the top of the body 10 through a lug 37 extended partially over a recess 38 within the body 10 wherein the bell crank 34 is located. A spring 39 acts 10 against the bell crank 34 so as to normally extend the peg 36 and retract the plate 32. When the rail is put in place it depresses the peg 36 which causes the extension of the catch plate 32 so that the clamp element 30 is held in place.

15 The main feature of the invention is the cheapness of manufacture of the rail ties in conjunction with the efficiency of its operation. Because the body 10 with the projections 12 and 17 may be made from one piece of material the price is materially reduced. The U-shape of the projections 12 provides for extreme strength which is necessary in holding the rails in place without undue weight or excess material.

20 While I have shown and described the preferred embodiment of my invention, it is to be understood that I do not limit myself to the precise construction herein disclosed and the right is reserved to all changes and modifications coming within the scope of the invention as defined 25 in the appended claims.

Having thus described my invention, what I claim as new, and desire to secure by United States Letters Patent is:—

30 1. A rail tie, comprising a body element for extending transversely beneath a pair of rails and having a pair of top projections for engaging the outer sides of said rails, an inner pair of projections from said body on the top thereof and located towards the inner sides of said rails, clamp plates for engaging against the inner sides of said rails and formed with apertures engageable over said inner top projections, and means coactable with said inner projections for holding the clamp plates down, said first mentioned pair of projections being separate and removable from said body element and engaging in inclined recesses in the body element, and means for clamping said

movable projections within said recesses including a stem depressible by said rail, and means movable by the stem as depressed, to clamp said movable projections.

80 2. A rail tie, comprising a body element for extending transversely beneath a pair of rails and having a pair of substantially U-shaped top projections for engaging against the outer sides of said rails, the bends thereof being towards the rails and arms at right angles to the rails, an inner pair of projections from said body on the top thereof and located towards the inner sides of said rails, clamp plates for engaging against the inner sides of said rails and formed with apertures engageable over said inner top projections, and means coactable with said inner projections for holding the clamp plates down, said U-shaped projections being separate and removable from said body element and engaging in inclined recesses in the body element, and means for clamping said U-shaped projections within said recesses, including a depressible stem depressed by said rail for causing said means to do the clamping.

85 3. A rail tie, comprising a body element for extending transversely beneath a pair of rails and having a pair of substantially U-shaped top projections for engaging against the outer sides of said rails the bends thereof being towards the rails and arms at right angles to the rails, an inner pair of projections from said body on the top thereof and located towards the inner sides of said rails, clamp plates for engaging against the inner sides of said rails and formed with apertures engageable over said inner top projections, and means coactable with said inner projections for holding the clamp plates down, said U-shaped projections being separate and removable from said body element and engaging in inclined recesses in the body element, and means for clamping said U-shaped projections within said recesses, including a depressible stem depressed by said rail for causing said means to do the clamping, said clamping means including a plate 95 slidably in said body and extendible into an opening in said U-shaped projection.
